US00D588630S

(12) **United States Design Patent**
Erzen et al.

(10) **Patent No.:** US D588,630 S
(45) **Date of Patent:** ** Mar. 17, 2009

(54) **PAYMENT DEVICE**

(75) Inventors: **Klemen Erzen**, Preddvor (SI); **Janez Staric**, Domzale (SI)

(73) Assignee: **ULTRA Proizvodnja elektronskih naprav d.o.o. (SI)**

(**) Term: **14 Years**

(21) Appl. No.: **29/297,450**

(22) Filed: **Nov. 12, 2007**

(51) **LOC (9) Cl.** **18-01**

(52) **U.S. Cl.** **D18/4.6**

(58) **Field of Classification Search** ..... D14/336, D14/371, 373-376, 385-387, 399; D18/3.1-3.3, D18/4.1-4.6, 6-8, 11, 12, 12.1-12.3, 19; D21/324, 329, 332, 333; D99/28, 34-36, D99/43; 235/1 E, 2, 7 R, 12, 22, 33, 51, 235/52; 705/12, 15-18, 43

(57) **CLAIM**

The ornamental design for a payment device, as shown.

DESCRIPTION

FIG. 1 is a front view of a payment device showing the present invention;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof; and,

FIG. 7 is a perspective view thereof.

The broken lines depict environmental subject matter only and form no part of the claimed design.
